GEORGE B. MILLIGAN, OF BALTIMORE, MARYLAND, ASSIGNOR TO T. POULTNEY, OF SAME PLACE.

Letters Patent No. 80,199, dated July 21, 1868.

IMPROVEMENT IN HORSE-SHOES.

The Schedule referred to in these Letters Patent and making part of the same.

TO ALL WHOM IT MAY CONCERN:

Be it known that I, GEORGE B. MILLIGAN, of Baltimore, of Baltimore county, in the State of Maryland, have invented certain new and useful "Improved Supplemental Horse-Shoe;" and I do hereby declare that the following is a full and exact description thereof, reference being had to the accompanying drawings, making part of this application.

My invention relates to certain new and useful improvements in devices or appliances for "roughing" horses' shoes.

Previous to my invention, two methods of changing the condition of horses' shoes, to suit different kinds of footing, have been suggested, and generally employed. One plan practised has been to remove the ordinary shoe from the horse's foot, and put ice-calks or projections on the shoe, (to prevent slipping on the ice;) the other plan has been to apply to the shoe, (while on the horse's foot,) adapted to receive such appliances, either steel points, screwed into or otherwise secured to the shoe, or a false shoe provided with points, clamped or otherwise secured to the shoe.

The last-named method appears, from experiment and experience, to possess the greatest utility, and the false shoe, provided with the ice-points, appears to be the most desirable means for carrying out this method of "roughing" the horse's shoes without removing them from the feet.

The main difficulties encountered in carrying into practice successfully this method, or the use of "false shoes," have been in providing a false shoe, which, while it was efficient and light, might be securely or rigidly attached to the horse's shoe, and could be expeditiously applied and removed by any one. To overcome these difficulties, false shoes have been so made that they could be applied to and apparently securely clamped on to the lower side of the shoe of the horse, without any provision in the shoe for the introduction of screws or other analogous mechanical securing-devices, but it has been found that where the false shoe is so clamped on, it cannot be wholly relied upon, and as the slightest liability of the "casting" of the false shoe renders the use of the latter most objectionable, it is very important to overcome this objection, which is the main object of my invention; and to this end my invention consists in so forming the false shoe, and preparing the ordinary shoe to receive it, that the false shoe and permanent shoe may be securely interlocked and coupled together by expanding the false shoe into suitable depressions in the permanent shoe, as will be presently more fully explained.

To enable those skilled in the art to make and use my invention, I will proceed to describe it more fully, referring by letters to the accompanying drawings, in which—

Figure 1 is a top view of an ordinary horse-shoe, adapted to receive and having applied to it a false shoe, according to my invention.

Figure 2 is a bottom view of the same.

Figure 3 is a vertical section at *x x*, fig. 1, and

Figure 4 is a vertical cross-section at *y y*, fig. 1.

In the several figures, the same parts are designated by the same letters of reference.

A is an ordinary horse-shoe, but formed or provided with two notches or cuts at *b b*, and with a depression at *c*, into which fit certain projections or lugs of the false shoe, as will be presently explained.

The false shoe is formed of two parts, *D D*², hinged or pivoted together at *e*. Each portion is provided with ice-calks or points, *f f*² and *g g*², as clearly illustrated, and also with projecting shanks, *h* and *h*². One of these shanks, *h*, is tapped, to receive the thread of a male screw, *i*. The other, *h*², is hollowed out slightly, to form a seat for the conical head of said screw *i*, (see fig. 2,) and said screw is provided with a jam-nut, *m*.

From the inner edge of each portion of the false shoe, near the heel, project upward lugs *o p*, and each of these lugs fits into one of the cuts or slots *b b*, and at the toe-portion of said false shoe is a projecting lip or hook, *s*, which interlocks with or fits into the depression *c* of the permanent shoe, (all as clearly illustrated.)

The cuts b are made to taper outward a little, and the projecting lugs o are correspondingly tapered, so that when adjusted to a complete bearing in the said cuts b , the false shoe is held firmly to the permanent shoe, and cannot pull downward, (see fig. 4.)

The operation may be thus briefly explained: When it is desired to apply or attach the false shoe to the permanent shoe, the hinged parts, $D D^2$, are moved together sufficiently (the jam-nut m being turned back, and the screw i turned in, sufficiently to permit it) to allow the ready adjustment to the permanent shoe, by slipping the lip s into its depression or seat, and the lugs o into their cuts or seats b . The screw i is then turned out, (or unscrewed,) its head bearing against the shank h^2 , and its thread against shank h , until the hinged portions of the false shoe are spread apart or expanded sufficiently to bring the lugs o home tight into the tapering cuts b , when the jam-nut m is run up, to insure the retention of the parts in this condition.

The false shoe is now rigidly or firmly coupled to the permanent shoe in a most reliable manner.

Whenever it is desired to remove the false shoe, the hostler has only to apply his wrench to the jam-nut m and screw i , and allow the hinged portions $D D^2$ to swing together, and release the lugs from the cuts b , when the said false shoe may be taken off without any trouble.

It will be seen that by means of the notches and interlocking projections, the false and permanent shoes are securely coupled together, while at the same time there are no screw-holes or screws to be applied, or other devices, which are liable to derangement, and to become inoperative.

Of course, the size and shape of the cuts or depressions of the permanent shoe, and of the interlocking projections of the false shoe, may be varied or transposed, and their positions and number may be changed, without departing from the gist of my invention.

By positively interlocking the parts, as shown, the false shoe is so secured to the permanent shoe that it cannot possibly have any longitudinal play, or slip back and forward on the permanent shoe, even if the clamping mechanism be not perfectly and tightly adjusted. It will be understood, therefore, that a great advantage is thus gained over that kind of appliance in which the false shoe is held longitudinally only, by being clamped against the plane inner edge of the permanent shoe.

The uses and advantages of false shoes for "roughing" are so well known to those who shoe and keep horses, that I need not here refer to them.

It will be seen that while the false and permanent shoes, adapted to be clamped and positively interlocked in the manner shown, are simple, and economic of manufacture, the ends and objects aimed at are most efficiently attained.

I am aware that an expanding false shoe, adapted to be clamped on to the ordinary shoe, is old, and that false shoes and ice-points have been attached to the horse's shoe by means of screws and bolts. I do not, therefore, wish to be understood as claiming separately either an expanding shoe, or a permanent securing of the "roughing" device to the horse's shoe; but having fully explained my new method of forming and adapting to each other the expanding false shoe and permanent horse-shoe,

What I claim as new, and desire to secure by Letters Patent, is—

An expanding false shoe, provided with interlocking projections, adapted to suitable depressions in the permanent shoe, or the equivalents thereof, for the purpose of firmly securing the roughing or false shoe and the permanent shoe together, as and for the purposes set forth.

I also claim the employment of an interlocking lip or hook, s , in combination with the false shoe, and adapted to operate in the manner and for the purposes substantially as described.

In testimony whereof, I have hereunto set my hand and seal, this seventh day of April, 1868.

GEORGE B. MILLIGAN. [L. S.]
